OSCILLATION GENERATOR

Victor J. Andrew, Wooster, Ohio, assignor to
Westinghouse Electric & Manufacturing Com-
pany, a corporation of Pennsylvania

Application April 8, 1931. Serial No. 528,555

2 Claims. (Cl. 250—36)

My invention relates to an oscillation generator and more particularly to novel improvements therein for the accomplishment of certain desirable results.

5 It is a well known phenomenon that, in oscillation generator circuits embodying thermionic devices, the frequency of the generated oscillation is a function of the grid-to-filament and of the plate-to-filament resistances. Furthermore, the 10 grid-to-filament and the plate-to-filament resistances severally are functions of the amplitude of oscillations in the grid and plate circuits.

A regeneration control, constructed according to teachings of the prior art will, therefore, produce changes in the frequency of the generator when the amplitude of oscillations is altered. A 15 regeneration control, comprising a means for varying the potential on the plate of an oscillator, is widely used because the effect of this control 20 on frequency is small. While the effect on the frequency might be too small to be considered as a serious disadvantage in most radio circuits, the problem of reducing or eliminating the effect becomes one of paramount importance when such 25 oscillators are to be calibrated and employed in frequency-measuring systems for measuring either audio or radio frequencies.

One object of my invention is to provide a 30 method of controlling regeneration in an oscillator without producing a resultant frequency change.

Another object of my invention is to provide an oscillation generator capable of maintaining a substantially constant-frequency output.

35 Another object of my invention is to provide an oscillation generator wherein the above objects are accomplished in a very simple and effective manner.

Additional objects will be disclosed in the following description of my invention.

In the accompanying drawing, Figure 1 is a 40 diagram of apparatus and circuits and Fig. 2 a curve diagram illustrating the theory of operation of my invention, as applied to an oscillator of the Colpitt type, together with circuit characteristic curves, although it should be understood that my invention is not necessarily limited, in its operation, to the above mentioned circuit, but may be incorporated in an oscillation generator of practically any type with equally good results.

An oscillator of the type mentioned comprises a thermionic device 1 having an anode 3, cathode 5 and grid 7 and an oscillatory circuit associated 45 therewith comprising a pair of serially-connected

variable capacitors 9 and 11 shunted by an inductor 13. As illustrated in the figure of the drawing, the filament is tied into the oscillatory circuit at a point 15 intermediate the capacitors 9 and 11, the anode being connected in at one 60 extremity 17 of the inductor and the grid being connected to the other extremity 19 through a grid condenser 21. The customary grid-leak resistor 23 is provided as shown.

Utilizing a circuit comprising only the elements outlined above, if a source of potential applied to the anode of the thermionic device were varied as a means of controlling regeneration, the frequency of the oscillator would be found to change somewhat as indicated by the 65 curve M—M of Fig. 2. The total change indicated represents but a very small increase in frequency which while ordinarily not troublesome would be undesirable for frequency measuring work.

The curve N—N of Fig. 2 represents the effect 70 on the frequency of the oscillator produced by variations in a resistor or other impedance which might be connected in shunt relationship to the oscillating circuit or to a portion thereof.

It will be noted that the effects in the two cases 75 are the reverse of each other, the frequency, in the one case, increasing with an increase in plate potential and that in the other case decreasing with an increase in resistance.

The condition which is to be desired in an 80 oscillator would be represented by the horizontal dotted line O—O of Fig. 2 which indicates no change in frequency for changes in regeneration.

I have found it possible to approach this ideal 85 condition very closely, as illustrated by curve Q—Q of Fig. 2, by superimposing, in the same circuit, the reverse effects noted above, the tendency of the frequency to increase due to one effect being substantially neutralized by the 90 tendency of the frequency to decrease because of the other effect. This method constitutes an important feature of my invention.

The above result is accomplished, in a very 95 simple manner, by modifying the oscillator described above. Referring back to Fig. 1, I provide a source of plate potential 25 connected in series with a plurality of resistors 27, 29, 31 between the filament and the grid end 19 of the oscillating circuit, the source 25 and resistance 27 being by-passed by a capacitor 33 of low impedance at the oscillation frequency, an approximate value of the capacity being .01 mfd.

A control element, comprising a variable resistor 35, is connected in parallel with the source 100 105 110

of potential and one or both of the resistances 27 and 29, for example, to provide regeneration control through variation of plate potential on the anode of the thermionic device.

5 In the position described, the variable resistor, in combination with resistor 31, also constitutes an impedance connected in shunt relationship to the condenser 9 which comprises a portion of the oscillating circuit, thereby fulfilling the conditions for producing a decreasing-frequency tendency.

Therefore, by the simple operation of altering the value of the resistor 35, I am enabled to control regeneration in the circuit and, at the same time, substantially neutralize the rising frequency characteristic of the circuit to obtain a substantially constant frequency output, regardless of the plate-potential variations.

15 The degree of constancy will depend somewhat upon the values of the resistors 27, 29, 31 in the circuit. Excellent results have been obtained in the following cases where the values of resistors 29 and 31 bearing the ratio of approximately 1.4 to 1 were employed:

Resistors	#27	#29	#31	#35
1	0Ω	30,000Ω	20,000Ω	50,000Ω
2	30,000Ω	4,000Ω	3,000Ω	50,000Ω

30 Resistor #27 may be dispensed with as it does not enter into the fundamental operation of the

system. Its function, primarily, is that of a battery filter resistor and, accordingly, is not an essential element, although its function is useful.

A glance at the curves of Fig. 2 will serve to indicate the constancy of frequency obtained in an oscillation generator, as a result of my invention.

While I have disclosed my invention in great detail, I do not desire to be limited thereby except insofar as is necessitated by the prior art 85 and by the appended claims.

I claim as my invention:

1. In combination, an oscillation generator comprising a potential supply source and an oscillatory circuit, said supply source being connected across a portion of said oscillatory circuit and an impedance in shunt to both said supply source and said portion of said oscillatory circuit whereby undesired changes in frequency of said generator arising out of changes in applied potential will be substantially balanced out. 95

2. In combination, an oscillation generator comprising a source of potential and an oscillatory circuit including a condenser and a coil, said source of potential being connected across said condenser, and a variable resistor in shunt to said source of potential and said condenser whereby changes in frequency of said generator due to changes in potential from said supply source will be substantially balanced out. 105
